FOLDING CHAISE LONGUE

Burnell E. Weirick, Kalamazoo, Mich., assignor to
Kalamazoo Sled Company, Kalamazoo, Mich.

Application July 14, 1941, Serial No. 402,272

11 Claims. (Cl. 155—45)

This invention relates to improvements in folding chaises longues.

The main objects of this invention are:

First, to provide a folding chaise longue or garden chair which is automatically adjustable from a position enabling an upright sitting posture to a fully reclined posture, or to any position intermediate these extremes, as desired by the user.

Second, to provide a chair structure of the foregoing type which is exceedingly simple in its parts and relatively stable in erected position, and which is capable of being quickly and easily collapsed to a highly compact form for shipment or storage.

Further objects relating to details and economies of my invention will appear from the description to follow. The invention is defined in the claims.

A structure embodying the features of my invention is illustrated in the accompanying drawings, wherein:

Fig. 1 is a side perspective view illustrating a chair or chaise longue embodying my invention, the parts being shown in one adjusted position thereof.

Fig. 2 is a view in side elevation illustrating the chair adjusted to a reclining position.

Fig. 3 is a view in side elevation illustrating the parts in partially collapsed position.

Fig. 4 is a fragmentary view in side elevation illustrating the parts when fully collapsed.

Fig. 5 is a fragmentary top plan view illustrating the foot end of the chair in its erected position, and

Figs. 6 and 7 are enlarged fragmentary views in section on lines 6—6, 7—7, respectively, of Fig. 1, further illustrating certain detail relationships of the parts.

The present collapsible chaise lounge or garden chair structure includes various seat, back, arm and strut members or elements operatively associated with one another in such manner that a very comfortable and stable support is provided in any adjusted position of the parts. At the same time the highly simplified character of the parts enables the construction to be readily collapsed for shipment or storage.

Referring to the drawings, the reference numeral 1 in general designates the folding lounge chair or chaise longue of my invention, including an elongated combined seat and leg rest member 2 having elongated rigid parallel side bars 3. Intermediate these bars adjacent the front end of member 2, I provide a plurality of

elongated, parallel slats 4 secured at their ends to the transverse bars 5 which extend between the side bars 3 intermediate their ends. These slats preferably rest on a transverse rod 6 which constitutes a stop or abutment for the front leg unit 7 pivoted to the side bars 3 at 8.

The reference numeral 9 in general designates a back or back rest member including rigid side bars 10 provided adjacent the lower end thereof with bracket-like pivot plates 11. The seat side bars 3 are pivoted to these plates at 12. It will be noted that a portion 13 of the back side members 10 projects downwardly beyond pivot plate 11 so as to engage the bottom surface of the seat member bars 3 in the full reclining position of the members 2, 9, illustrated in Fig. 2, thus preventing further pivotal movement of the members relative to one another in that direction.

The back member side bars 10 are connected by a transverse rod 14 at the top thereof and the seat member side bars 3 having a similar transverse rod 15 intermediate the length thereof and rearwardly of the foot supporting slat unit. (See Fig. 5.) A flexible canvas web back and seat element for supporting the body of the user is secured at its opposite ends to the transverse rods 14 and 15, and if desired, further transverse flexible canvas webs 17, 18 may be stretched across the structure between the rear member side bars 10 and the seat member side bars 3, respectively, to reinforce the support provided by the flexible canvas web 16. Likewise, a continuous elongated cushion or pad 20 may be stretched lengthwise of the structure over the aforesaid canvas webs, being secured at its opposite ends to the rod 14 and transverse bar 5, respectively.

A pair of arms or arm rests 21 are pivoted to a pivot plate 22 located intermediate the length of the back member 9, about one foot above the pivot plate 11. These arm rests are likewise pivotally connected adjacent their forward ends to the upper ends of a pair of arm braces 23 by means of pivot plates 24, the arm braces 23 being in turn pivoted at their lower ends to the side bars 3 intermediate the ends thereof. The last named pivot point 25 is spaced from the pivot 12 of the seat and back members a distance equal to the distance between the arm pivots on the plates 22 and 24, respectively. Coincident with the pivot point of arm braces or bars 23 on the arm pivot plates 24, the said braces and arms have pivoted thereto the forwardly inclined rear leg unit 26, including leg side bars 27 pivoted to plates 24, transverse crossed bracing slats 28 and

wheels 281 rotatably mounted on bars 27 adjacent the lower rear ends thereof for rolling engagement with the ground or other supporting surface.

Coincident with the pivot point of arm rests 21 on the rear member pivot plate 22, the said arms likewise have pivoted thereto the strut bars 29 which project downwardly and forwardly for end abutting engagement with the rear leg side bars 27 intermediate the length of the latter and forwardly projecting fingers 30 on the free ends of strut bars 29 are provided for engagement with the inner surfaces of the leg bars 27 to maintain alignment and prevent lateral play. The strut bars 29 are connected to the leg bars 27 adjacent their pivotal connection to the arms and braces 23 by the links 31.

In use, the chair is set up in the manner illustrated in Fig. 1, with the swinging ends of the strut bars 29 abuttingly engaging the rear surface of the leg side bars 27 of the rear leg unit 26, the back member 9 being swung partially rearwardly in counter-clockwise direction to a desired angular relationship to the seat member. The rear leg unit is swung rearwardly in clockwise direction about its pivots until it engages strut bar 29. This provides a very stable support. If the user desires to fully recline he merely stretches out and leans backwardly somewhat, causing the back member 9 of the chair to pivot about its pivot 12 to the seat member 2 until the parts assume the position shown in Fig. 2. During this relative swinging of the seat and back members 2, 9, respectively, the leg unit 26 rolls rearwardly on its wheels 281 and the arm rests 21 shift somewhat relative to the arm brace and strut bar 23, 29, respectively, however the last named strut bar continues to abuttingly engage the leg 27, being maintained in engagement therewith by the connecting link 31. It will be understood that the structural elements above referred to are duplicated on each side of the chair structure although in certain cases in the above description I have referred only to single elements.

It will be appreciated from the foregoing that the respective pivot points of the strut bar 29 and the rear legs 27 to the rear and front of the arm rests 21, the pivot point of arm brace 23 to seat member 2 and the pivot 12 of the seat and rear members define the corners of a parallelogram permitting free swinging of the parts in the aforesaid collapsing and erecting movements. Strut bar 29 locks this parallelogram against complete collapse in the rearward direction while enabling it to be collapsed forwardly as will presently be described. Enough friction is provided at the various pivotal connections to resist excessive looseness at the joints and enable the parts to maintain any position in which they are set.

The user may position himself in any one of many very comfortable reclining, semi-reclining or sitting positions. The chair is entirely automatic in these movements, no special provision being needed for the adjustments. The parts are exceedingly simple and in erected position are effectively braced and trussed so as to resist looseness or wobbling at the pivotal connections.

The chair may be easily collapsed for storage or shipment by merely pivoting the rear member 9 forwardly in clockwise direction relative to the seat member about pivot 12, as illustrated in Fig. 3, bringing these members into parallelism. The front legs 7 are then swung rearwardly into

parallel, telescoped relation on the inner sides of the seat member bars 3, and as a final step the rear leg unit 26 is swung forwardly in counter-clockwise direction about its pivot to the arms 5 to bring the same in side by side relation to the bottom of the seat member 2 at the front end thereof. This operation is performed in a very few seconds time and results in a compact, collapsed relation of the parts, as illustrated in Fig. 4.

The free shiftability of the strut bar 29 makes possible this highly compact collapsing of the parts, swinging forwardly and upwardly counter-clockwise as leg unit 26 is brought to collapsed position. Notwithstanding this, strut bar 29 effectively braces and supports the seat and back members 2, 9 in erected position, forming with the legs 27 engaged thereby and the pivotally connected arm rests 21 and arm braces 23, a truss construction which effectively resists wracking or undesired collapse.

It should be noted that the pivot plates or brackets 11, 24 and 25 all project from the member to which they are fixedly secured so that the 15 part pivoted thereto may collapse flat against the part carrying the pivot member.

An embodiment of the invention which incorporates the principles of the invention in a highly desirable manner has been illustrated and described. It should be understood that the foregoing terminology is used descriptively rather than in a limiting sense, and with full intention to include equivalents of the features shown and described, within the scope of the following 30 claims.

Having thus described my invention, what I claim as new and desire to secure by Letters Patent is:

1. A collapsible chair or lounge structure, comprising pivotally connected seat and back members swingable 180° relative to one another from a collapsible position in side by side parallelism to selected angularly related positions including a fully erected reclining position in which the 40 back member constitutes an extension of the seat member, arms pivotally connected to said back member to project forwardly thereof above the seat member in approximate parallelism therewith in erected position, arm supporting bars 45 pivotally connected to the forward ends of said arms and to said seat member intermediate the length thereof, a rear leg unit pivoted to said arms at the pivot point of the supporting bars thereto, said leg unit being inclined downwardly 50 and rearwardly from said pivot point and provided with wheels rollingly engageable with a supporting surface, strut bars pivotally connected to said arms at the pivot of the latter to the back member, the free end of said strut bars abuttingly 55 engaging the rear of said inclined leg unit in operative position thereof to maintain the arms in approximate parallelism with the seat member, and link means pivotally connected at its ends to said free ends of the strut bars and to 60 said leg unit above the point of abutting engagement of the strut bars therewith, said leg unit being collapsible forwardly and upwardly beneath said seat member and said link means being actuated by said last named collapsing movement to 65 elevate said strut bars into inoperative position in close, approximately parallel adjacency to said arms.

2. A collapsible chair or lounge structure, comprising pivotally connected seat and back members swingable 180° relative to one another from 70 75

a collapsible position in parallelism to selected angularly related positions including a fully erected reclining position in which the back member constitutes an extension of the seat member, arms pivotally connected to said back member to project forwardly thereof above the seat member in approximate parallelism therewith in erected position, arm supporting bars pivotally connected to the forward ends of said arms and to said seat member intermediate the length thereof, a rear leg unit pivoted to said arms at the pivot point of the supporting bars thereto, said leg unit being inclined downwardly and rearwardly from said pivot point and having movable engagement with a supporting surface, strut bars pivotally connected to said arms at the pivot of the latter to the back member, the free end of said strut bars abuttingly engaging the rear of said inclined leg unit in operative position thereof to maintain the arms in approximate parallelism with the seat member, and link means pivotally connected at its ends to said strut bars and to said leg unit in offset relation to the point of abutting engagement of the strut bars therewith, said leg unit being collapsible forwardly and upwardly beneath said seat member and said link means being actuated by said last named collapsing movement to elevate said strut bars into inoperative position in close, approximately parallel adjacency to said arms.

3. A collapsible chair or lounge structure, comprising pivotally connected seat and back members swingable from collapsed position to selected angularly related positions, arms connected to said back member, a rear leg unit pivoted to said arms, said leg unit being inclined downwardly and rearwardly and having movable engagement with a supporting surface, strut bars pivotally connected to said arms, the free ends of said strut bars abuttingly engaging the rear of said inclined leg unit in operative position thereof, and link means pivotally connected at its ends to said strut bars and to said leg unit in offset relation to the point of abutting engagement of the strut bars therewith, said leg unit being collapsible forwardly and upwardly beneath said seat member and said link means being actuated by said last named collapsing movement to elevate said strut bars into inoperative position.

4. A collapsible chair or lounge structure, comprising pivotally connected seat and back members swingable to selected angularly related positions, arms connected to said back member, a rear leg unit pivoted to said arms, said leg unit being inclined downwardly and rearwardly and provided with wheels rollingly engageable with a supporting surface, strut bars pivotally connected to said arms, the free end of said strut bars abuttingly engaging the rear of said inclined leg unit in operative position thereof, and link means pivotally connected at its ends to said free ends of the strut bars and to said leg unit above the point of abutting engagement of the strut bars therewith, said leg unit being collapsible forwardly and upwardly beneath said seat member and said link means being actuated by said last named collapsing movement to elevate said strut bars into inoperative position.

5. A collapsible lounge structure, comprising pivotally connected seat and back members swingable 180° relative to one another from an inoperative collapsed position in side by side parallelism to the fully erected reclining position

in which the back member constitutes an extension of the said member, arms pivotally connected to said back member, arm supporting bars pivotally connected to said arms and to said seat member, a rear leg unit pivoted to said arms adjacent the pivotal point of the braces thereto, said leg unit being inclined downwardly and rearwardly from said pivot to the arms and having movable engagement with a supporting surface, and strut means pivotally connected to said arms adjacent the pivot of the latter to the back member, said strut means abuttingly engaging said inclined leg unit in operative position thereof, and being pivotally connected to said leg unit above the point of the abutting engagement of the strut means therewith, said leg unit being collapsible forwardly beneath said seat member and simultaneously actuating said strut means to inoperative position to said arms.

6. A collapsible lounge structure, comprising pivotally connected seat and back members swingable 180° relative to one another from an inoperative collapsed position in side by side parallelism to the fully erected reclining position in which the back member constitutes an extension of the said member, arms pivotally connected to said back member, a rear leg unit pivoted to said arms, said leg unit being inclined downwardly and rearwardly from said pivot to the arms and having movable engagement with a supporting surface, and strut means pivotally connected to said arms adjacent the pivot of the latter to the back member, said strut means abuttingly engaging said inclined leg unit in operative position thereof, and being pivotally connected to said leg unit in spaced relation to the point of the abutting engagement of the strut means therewith, said leg unit being collapsible forwardly beneath said seat member and simultaneously actuating said strut means to inoperative position to said arms.

7. A collapsible chair structure, comprising a frame including pivotally connected seat and back members swingable relative to one another, means for limiting said swinging movement, and arm rests pivoted at the rear thereof to said back member, a leg unit pivoted to said frame having wheels on the free end thereof rollingly engageable with a supporting surface as said seat and back members are pivoted relative to one another, strut bars pivotally connected at one end to said frame and abuttingly engaging said leg unit at their opposite ends, and links pivotally connected to said leg unit adjacent the pivot point thereof to the frame and to said strut bars adjacent said opposite ends thereof, and maintaining said strut bars in predetermined relation to said leg unit in erected condition of the chair structure, said leg unit being swingable forwardly to collapsed position adjacent the seat unit and simultaneously retracting said link and strut bar to which the same is connected to inoperative position.

8. A collapsible chair structure, comprising a frame including pivotally connected seat and back members swingable relative to one another, means for limiting said swinging movement, and arm rests pivoted at the rear thereof to said back member, a leg unit pivoted to said frame, said unit being movably engageable with a supporting surface as said seat and back members are pivoted relative to one another, strut bars pivotally connected at one end to said frame and abuttingly engaging said leg unit at their opposite ends, and means pivotally connecting said leg unit adjacent

the pivot point thereof to the frame and said strut bars adjacent said opposite ends thereof, and maintaining said strut bars in predetermined relation to said leg unit in erected condition of the chair structure, said leg unit being swingable forwardly to collapsed position adjacent the seat unit and simultaneously retracting said last named means and strut bar to which the same is connected to inoperative position.

9. In a collapsible chair structure, pivotally connected seat and back members swingable relative to one another, an arm rest member pivoted at the rear thereof to said back member, a brace member pivotally connected to said seat member and to said arm rest member adjacent the front thereof, a leg unit engageable with a supporting surface at one end thereof and pivoted adjacent the other end thereof to said arm rest member at the pivot point of the rest and brace members, a strut pivotally connected to said rest and back members adjacent the point of pivotal connection thereof and abuttingly engaging said leg unit, and a link pivotally connected to said strut and to said leg unit adjacent the point of pivotal connection of the latter to said arm rest member, said leg unit being swingable to collapsed position adjacent the seat member and simultaneously retracting said link and strut to inoperative collapsed position.

10. In a collapsible chair structure, pivotally connected seat and back members swingable relative to one another, an arm rest member pivoted

at the rear thereof to said back member, a brace member sustaining said arm rest member, a leg unit engageable with a supporting surface at one end thereof and pivoted adjacent the other end

5 thereof to said arm rest member, a strut pivotally connected to said rest and back members adjacent the point of pivotal connection thereof and abuttingly engaging said leg unit, and a link pivotally connected to said strut and to said leg unit adjacent the point of pivotal connection of the latter to said arm rest member, said leg unit being swingable to collapsed position adjacent the seat member and simultaneously retracting said link and strut to inoperative collapsed position.

10 11. In a collapsible chair structure, pivotally connected seat and back members swingable relative to one another, an arm rest member pivoted at the rear thereof to said back member, a brace member sustaining said arm rest member, a leg unit engageable with a supporting surface at one end thereof and pivoted adjacent the other end thereof to said arm rest member, a strut pivotally connected to one of said rest and back members and abuttingly engaging said leg unit, and a link pivotally connected to said strut and to said leg unit adjacent the point of pivotal connection of the latter to said arm rest member, said leg unit being swingable to collapsed position adjacent the seat member and simultaneously retracting said link and strut to inoperative collapsed position.

BURNELL E. WEIRICK.
